UNITED STATES PATENT OFFICE.

GEORGE CLARK, OF CHICAGO, ILLINOIS.

STEAM-SEPARATOR.

No. 845,758.

Specification of Letters Patent.

Patented March 5, 1907.

Application filed September 21, 1905. Serial No. 279,407.

To all whom it may concern:

Be it known that I, GEORGE CLARK, a citizen of the United States, and a resident of Chicago, in the county of Cook and State of Illinois, have invented certain new and useful Improvements in Steam-Separators, of which the following is a specification.

This invention relates to improvements in that class of steam specialties known as "separators" and which are designed to be inserted in a line of steam-pipe to separate out the entrained water or the oil or other impurities which may be carried along with the steam.

The object of the invention is to provide an improved construction in devices of this character which shall be exceedingly efficient in operation while at the same time simple of construction and convenient of access for cleaning or repairs.

In the accompanying drawings, Figure 1 is a longitudinal section of a separator constructed in accordance with my improvements. Fig. 2 is a transverse section thereof, taken on line 2 2 of Fig. 1.

In said drawings, 1 designates the body of the separator, which, as herein shown, is of cast-iron and approximately melon-shaped, its greatest length lying along the direction 30 of the piping in which the separator is to be connected. To enable the separator to be connected to the piping, it is provided at its opposite ends with pipe-flanges 2 and 3, by which it may be bolted to the flanges of the 35 pipe-line in the usual manner. The interior of the casing thus formed is divided by a curved partition-wall 4 into receiving and outlet chambers 5 and 6, respectively. Of these the receiving-chamber 5 occupies the 40 larger and lower portion of the casing, while the outlet-chamber 6 is located at the top of the casing and is of crescent shape in cross-section, the partition-wall 4 being arched over parallel to the top wall of the casing to 45 divide the two chambers in the manner stated. A plurality of apertures 7 in said partition-wall located toward the inlet end of the casing afford communication between the two chambers and permit the steam to 50 flow from one to the other.

Extending longitudinally into the chamber 5 from the inlet end or flange 2 of the casing is a deflector or reaction-tube 8, the inner end of which is cut off obliquely, as 55 shown at 9, in such manner as to leave its

upper wall 10 continuous to the inner extremity 11 of the tube. This latter is shown as extending well toward the front end of the chamber 5 and as ending in proximity to but not in contact with the partition-wall 4 of 60 the casing, where said partition curves downwardly to permit the outlet-chamber 6 to merge into the outlet-opening 12 of the casing. Said upper wall 10 of this tube thus extends directly beneath the apertures 7 in the 65 partition-wall 4 and serves as a baffle-plate to prevent the steam from passing too immediately out through said apertures after it enters the separator and before the separating action takes place. Said upper wall 10 70 of the tube also serves as a reaction-plate against which the pressure of the steam exerts itself, so as to deflect or throw the current of steam downwardly toward the bottom of the receiving-chamber, this action 75 being aided by the downwardly-turned flange or lip 12, formed at the inner extremity of the tube 8.

Owing to their superior momentum a portion of the entrained water and of the oil and other impurities entering the separator with the steam will be thrown forward against the lower front end wall of the receiving-chamber and will trickle down said wall and collect in the bottom of the chamber; but the 80 greater portion of the entrained water and of the oil and other impurities will be at once thrown downwardly into the bottom of the receiving-chamber, following the changed line of direction of the steam. This action 85 is aided by the fact that the oblique or inclined mouth of the pipe 8 will offer such free escape of the steam into the chamber 5 as to reduce its velocity and permit the water and oil to be more readily deposited, and it 90 will also be aided by the downwardly-turned lip 12, heretofore mentioned as located at the extreme inner end of the upper wall 10 of the pipe. Then when the particles of water, oil, and the like have thus been separated out 95 from the steam and collected in the bottom of the receiving-chamber the dry vapor will itself pass up and around the tube 8 and on into the outlet-chamber 6 through the passages 7.

An aperture 13, tapped to receive a drain-pipe, is provided in the casing at the lower front end of the receiving-chamber 5 to permit the oil and water to be drained off as they collect in said chamber, and the casing 110

is also provided at the lower front end of its receiving-chamber with apertures 14 for receiving the connections of a gage-glass, by which the depth of oil, water, and other impurities collected and standing within the receiving-chamber at any time may be determined at a glance. These apertures 14 are placed in a right-angular arrangement about the lower front or drainage corner of the chamber 5, and the gage-glass connections may be made between the corner aperture and either of the others, so that it will stand either parallel with or at right angles to the longitudinal axis of the separator, thus permitting the latter to be used either in a horizontal or a vertical position, as desired.

In order to further insure the separation and to overcome the tendency of the oil to creep along the surface of the receiving-chamber and be carried into the outlet-chamber by the flow of steam leaving the receiving-chamber, said receiving-chamber is provided at each side and through its length with downwardly-projecting ribs 15, which in the approved construction shown form the lower inner edges of the arched top or partition wall 4 of the chamber, Fig. 2. Then as the steam expands into the enlarged lower portion of the receiving-chamber and divides into two currents flowing toward the opposite sides of the chamber these currents will again be deflected by said ribs 15, so as to chute the oil and water downwardly into the bottom of the chamber while the steam flows back around the baffle-plate 8, any oil which is creeping along the surface under the flow of the current simply dripping back into the bottom of the chamber, while the current of steam passes on, as described.

For convenience of manufacture the tube 8 is herein shown as made separate from the rest of the casing and as flanged at its outer or inlet end to fit within a counterbore in the flange 2 of the casing, any suitable fastening devices, such as countersunk screws 16, being provided to hold the tube in place.

I claim as my invention—

1. A separator consisting of a casing having a receiving-chamber and an outlet-chamber communicating therewith through passages, and a reaction-tube extending into the receiving-chamber and opening obliquely into the latter away from said passages, the extended wall of said tube serving as a baffle-plate for said passages, substantially as described.
2. A separator consisting of a casing having a receiving-chamber and an outlet-chamber communicating therewith through passages, a baffle-plate within the receiving-chamber opposite the passages and between them and the inlet-opening of the separator, said baffle-plate being in the form of a tube through which the steam enters the receiving-chamber and being cut obliquely to com-

municate with said chamber, its oblique opening facing that side of the receiving-chamber remote from the communicating passages, substantially as described.

3. A separator consisting of a casing having a receiving-chamber, and a crescent-shaped outlet-chamber, separated from said receiving-chamber through an arched partition, and communicating therewith through passages in said partition, a reaction-tube extending into the receiving-chamber and opening obliquely into the latter away from said passages, the extended wall of said tube serving as a baffle-plate for the passages between its receiving and outlet chambers, substantially as described.

4. A separator consisting of a casing having a receiving-chamber and a crescent-shaped outlet-chamber communicating therewith through passages, and a reaction-tube extending into the receiving-chamber opening obliquely into the latter away from said passages, the extended wall of said tube serving as a baffle-plate for the passages between its receiving and outlet chambers and the extremity of said tube being flanged inwardly toward the open side of the tube, substantially as described.

5. A separator consisting of a casing having a receiving-chamber and outlet-passages leading therefrom, a baffle-plate within the receiving-chamber opposite said outlet-passages and between them and the steam-inlet of said chamber, said baffle-plate being of tubular form and opening obliquely into said chamber with its oblique opening facing away from the outlet-passages, substantially as described.

6. A separator consisting of a casing having a receiving-chamber and outlet-passages leading therefrom, a baffle-plate within the receiving-chamber opposite said outlet-passages and between them and the steam-inlet of said chamber, said baffle-plate being of tubular form and opening obliquely into said chamber with its oblique opening facing away from the outlet-passages, and lateral ribs in said receiving-chamber, substantially as described.

7. A separator consisting of a casing substantially circular in cross-section and having an inlet at one end and an outlet at the opposite end and an arched partition-wall within the casing, this arched wall being connected along its lower edges to the respective side walls of the casing to thereby form a crescent-shaped chamber and also being provided with perforations toward its rear portion, and an inlet-tube extending into the casing below the arched wall and to a point beyond the perforations therein.

8. A separator consisting of a casing having an inlet at one end and an outlet at its other end and a perforated arched partition-wall which converts the upper part of the

casing into an outlet-chamber, and an inlet-
tube extending into the chamber to a point
beyond the perforations and arranged to dis-
charge the steam toward the bottom of the
casing.

5 In testimony that I claim the foregoing as
my invention I affix my signature, in pres-

ence of two subscribing witnesses, this 14th
day of August, A. D. 1905.
